(57) **CLAIM**

The ornamental design for a cable organizer, as shown and described.

DESCRIPTION

FIG. 1. is a perspective view thereof;

FIG. 2. is a front elevational view thereof;

FIG. 3. is a rear elevational view thereof;

FIG. 4. is a left side elevational view thereof;

FIG. 5. is a right side elevational view thereof;

FIG. 6. is a top plan view thereof;

FIG. 7. is a bottom plan view thereof;

FIG. 8. is a perspective view of the cable organizer in an alternate position; and,

FIG. 9. is a perspective view of the cable organizer in a position of use.

The broken line structure in FIG. 9 showing the cable organizer in a position of use forms no part of the claimed design.
